DESIGN FOR A SERVICE BAR BACK COUNTER

Giraud W. Behrel, Chicago, and Herbert Tyson,
Oak Park, Ill., assignors to The Brunswick-
Balke-Collender Company, Chicago, Ill., a corporation of Delaware

Application February 21, 1936, Serial No. 61,287

Term of patent 3½ years

To all whom it may concern:

Be it known that we, Giraud W. Behrel and Herbert Tyson, both citizens of the United States, residing, respectively, in Chicago, in the county of Cook, State of Illinois, and in Oak Park, in said county of Cook, State of Illinois, have invented a new, original, and ornamental Design for a Service Bar Back Counter, of which the following is a specification, reference being had to the accompanying drawing, forming a part thereof.

In the drawing—

The figure is a perspective view of a service bar back counter showing our new design.

We claim—

The ornamental design for a service bar back counter as shown.

GIRAUD W. BEHREL.
HERBERT TYSON.
